TYPOGRAPHICAL MACHINE

Norbert Fucik, Chicago, Ill.

Application November 24, 1933, Serial No. 699,498

8 Claims. (Cl. 199—30)

The present invention relates generally to improvements in the line composing type casting machines of the well known linotype class, but more particularly to that portion of the machine known generally as the slide assembly.

Heretofore, it has been the practice to disengage the clutch of these types of machines to stop the travel of the matrix delivery belt, when one or more keys have been tripped by the operator, to discharge matrices which are in excess of the line previously set, in order to remove or provide space for the excess matrix or matrices. This practice not only causes delays and interrupts the continuous operation of the linotype machine, but also, under certain conditions, makes readjustment of the length of line necessary where an additional matrix is needed to complete the line. For example, where a twelve point letter like "m" is required to be substituted 20 in a line in place of a six point letter like "n".

It is therefore, one of the primary objects of my invention to overcome these difficulties and to provide a novel and improved construction which will permit the adding of an additional matrix or matrices to the line previously set without the necessity of interrupting the continuous operation of the matrix delivery belt and linotype machine.

A further object of the invention is to provide a simple and improved means for adjusting the width of the line or for releasing an offset line without stopping the operation of the matrix delivery belt.

A still further object of the invention is to provide a novel and improved braking mechanism for the slide bar.

A further object of the invention is to provide a novel and improved adjustment for the slide bar brake and a novel and improved means 40 for adjusting the spring tension of the brake.

A yet further object of the invention is to provide a novel and improved construction of an adjustable clamp which automatically locks to the slide bar upon a slight movement of the clamp block in either direction to the next succeeding locking recess in the slide bar so that the clamp may be quickly and readily adjusted a minimum distance of six point (printer type measurement) one way or another without any 50 unnecessary delay.

These and other objects are accomplished by providing a construction and an arrangement of the various parts in the manner hereinafter described and particularly pointed out in the appended claims.

Referring to the drawings:

Fig. 1 is a front elevational view of a fragmentary portion of a linotype machine having my improvements embodied therein;

Fig. 2 is a similar front elevational view showing the position of the various parts at the conclusion or completion of one line of matrices;

Fig. 3 is a cross sectional view taken on the line 3—3 in Fig. 2;

Fig. 4 is an enlarged fragmentary view showing the manner in which excess matrices jam into position adjacent the star wheel;

Fig. 5 is a similar view showing the manner in which the stop may be released for extending the slide bar and slide bar finger to accommodate 15 the excess matrices;

Fig. 6 is a fragmentary enlarged detailed view showing the construction of my improved slide bar braking mechanism;

Fig. 7 is a cross sectional view taken on the line 7—7, Fig. 2;

Fig. 8 is a cross sectional view taken on the offset line 8—8 in Fig. 6;

Fig. 9 is a cross sectional view taken on the line 9—9 in Fig. 7 with one of the pawls locked 25 in one of the recesses in the slide bar;

Fig. 10 is a similar cross sectional view with the other pawl locked in the nearest adjacent recess of the slide bar;

Fig. 11 is a perspective view of my improved 30 slide bar clamp;

Fig. 12 is a cross sectional view taken on the line 12—12 in Fig. 1;

Fig. 13 is a cross sectional view taken on the offset line 13—13 in Fig. 1;

Fig. 14 is a cross sectional view taken on the offset line 14—14 in Fig. 1;

Fig. 15 is a cross sectional view taken on the offset line 15—15 in Fig. 3;

Fig. 16 is a cross sectional view taken on the line 16—16 in Fig. 15;

Fig. 17 is a cross sectional view taken on the line 17—17 in Fig. 7;

Fig. 18 is a cross sectional view taken on the offset line 18—18 in Fig. 17;

Fig. 19 is a cross sectional view taken on the line 19—19 in Fig. 2; and

Fig. 20 is a fragmentary view taken on the line 20—20 in Fig. 19.

In illustrating one form of my invention, I 50 have shown the same in connection with the conventional form of linotype machine of which only a fragmentary portion of the same is shown in the drawings. This portion of the machine consists of a front plate generally indicated by the 55

reference character 25. Mounted on the front plate 25 is a driven roller 26 about which is trained the matrix delivery belt 27 which conveys and delivers the matrices generally shown at 28 from the magazine to the matrix assembler 29'. Extending through the front plate 25 is the usual clutch control 29 for controlling the operation of the matrix delivery belt. Positioned adjacent the delivery end of the belt 27 is the usual star wheel 30 for feeding the matrices in their normal position on the supporting assembler 29'. Pivotally connected, as shown at 31, to a lower portion of the front plate 25, is a space band buffer 32 which is adapted to be engaged by space bands 33.

One of the essential features of the present invention consists of the novel slide bar and its associated devices therewith which permits the operator to quickly adjust the width of the line and to quickly release an overset line without the necessity of stopping the matrix delivery belt, thereby saving considerable time and permitting these adjustments to be made without interrupting the continuous operation of the linotype machine. This mechanism comprises a slide bracket 25' which is secured in spaced relation with respect to the front plate 25 by bolts 26' and spacer collars 27'. Reciprocally mounted on the slide bracket 25' is a novel slide bar, generally indicated by the reference character 34, which is preferably channel-shape in form, as is clearly shown in Figs. 11 to 16 inclusive. Mounted within the channel portion of the slide bar 34 is the usual graduated scale 35 in which the smaller graduations represent six point of the standard printers type. This bar is reciprocally mounted in a rectangular recess 38 formed in the slide bracket 25'. The bar 34 is prevented from displacement in the recess 38 by a plate in the form of an angle member 39 secured to the slide bracket 25' by means of screws 40. (See Figs. 1, 2 and 7.) This plate 39 is provided with a forwardly projecting flange as shown at 41. On one side of this flange is vertically extending dovetail shaped recess, as shown at 42. Mounted in this vertical recess 42 is a reciprocable dove-tail shaped member 43 which has formed integrally adjacent the bottom therewith, a finger trip 44. This reciprocable member 43 is held in its uppermost position with respect to its guide 41 by a spring 45 which has one end thereof connected to a screw 46 attached to the flange 41 of the bracket 39. (See Figs. 7, 15 and 16.) The lower end of the spring 45 is attached to a screw 47 which in turn is secured to the reciprocable member 43. The screw 47 extends through a vertical slot 48 formed in the lower portion or flange 41. The reciprocable member is limited in its vertical movement by a stop screw 49 secured to one side of the flange 41. This stop screw 49 extends through a slot 50 formed adjacent the upper end of the member 43. Adjustably mounted in threaded engagement in a bore 51 of the reciprocal member 43, is an adjustable stop screw 52 which is locked in various positions of adjustment by a lock nut 53. One end of this stop screw 52 is provided with a reduced portion 54 which is adapted to engage or contact with my improved form of clamp for limiting the movement of the slide bar when the predetermined number of matrices have been discharged to complete the line. Obviously from the above description, it will be seen that when an excess number of matrices have been discharged so as to clog up the assembler 29' adjacent the star wheel 30, as clearly shown in Fig. 4 of the drawings, the

finger trip 44 may be depressed from the position shown in Fig. 15 to the position shown in Fig. 5, thereby removing the stop 54 of the screw 52 from the clamp and permitting the bar to move an additional distance to the left, as shown by the dotted lines in Fig. 5 so as to accommodate excess matrices without disengaging the clutch of the matrix delivery belt or interrupt the continuous operation of the linotype machine. It will also be obvious from the above description, that should the star wheel, which is preferably made of fibre, become worn, or the old one replaced by a new one, the stop screw 52 may be adjusted with respect to the vertical movable member 43 to take care of this variation.

Another essential feature of the present invention involves my improved construction of slide clamp in combination with a novel construction of slide bar in which the sliding bar has a coarse graduation of "six point" teeth with each of the recesses between the teeth occupying "six point" (printers type measurement). This coarse graduation or division on the slide bar simplifies the manufacture of this particular part and in combination with my improved clamp, permits the clamp to be adjusted to a graduation of "six point" at a time and at any position on the sliding bar which is the finest adjustment necessary or required in this type of machine. In other words, my novel form of clamp permits minimum adjustment of the same with respect to the slide bar, a distance equal to one-half the distance between two adjacent teeth. This improved mechanism includes the slide bar 34, which has its upper forward edge provided with equally spaced apart tapered recesses 55 of "six point" width with corresponding equally spaced apart teeth 56 between each of the recesses 55. These teeth are also of "six point" width. In other words, the graduations on the present slide bar are twice as coarse as those heretofore used in connection with slide bars for securing the same adjustment. Adjustably mounted in a rectangular recess 57 on the bar 34 is my improved form of clamp, generally indicated by the reference character 58, which is in the form of a cubical block. (See Figs. 7, 9, 10, 11, 17, 18 and 19.) Located in the upper portion of the clamp block 58 are two equally spaced apart recesses or slots 59 and 60. Pivotally mounted on a transverse pin 61 and in the slots 59 and 60, are pawls 62 and 63. The inner portion of these pawls are pointed as shown at 64 and are adapted to be seated in the various recesses 55 of the sliding bar 34. These pawls and particularly the center line passing through the pointed portion thereof, are spaced apart at "eighteen points" with respect to each other. The forward portion of the pawl 62 and 63 are normally pressed into engagement with the recesses 55 of the sliding bar 34 by springs 65 mounted in vertically extending bores 66 located in the block 58. The upper ends of these springs are connected as shown at 67, to each of the pawls inwardly of their pivots 61 on the block 58. The lower ends of these springs are connected by means of a pin 68 to the block 58. Obviously from the above description, it will be readily seen that the outer ends of the pawls 62 and 63 may be depressed to disengage their inner ends from recesses 55 in the sliding bar 34 for adjusting the clamping blocks 58 in either direction on the bar and when the approximate position has been secured, as indicated by the graduated scale 35, the pawls are released. If a further adjustment one

way or another is required, the locked pawl may be disengaged and the clamp shifted in one direction or the other in which case the free pawl will automatically lock in the next succeeding recess, after a movement of clamps a distance of six points in either direction.

Another important feature of the present invention includes the provision of a novel and improved slide bar brake and adjustment therefore for varying the spring tension on the braking mechanism when such adjustment is required. This mechanism comprises the usual offset arm 69 of a braking lever which has its free end as shown at 70 extending beneath the assembler 29, which receives the matrices so that the same may be actuated in the manner well understood in the art, by the assembled elevator bar 71, a fragmentary portion of which is shown in Fig. 6 of the drawings. The pivoted end of this arm 69 is provided with an eye, as shown at 72, and is pivotally supported on a sleeve 73, which in turn is formed integrally with a knurled collar as shown at 74. Pivoted concentrically with the pivoted portion 72 of the arm 69, as shown at 75, is a second brake arm 76. (See Figs. 6, 8, 12, 13 and 14). The arm 76 is yieldable with respect to the arm 69 through the medium of a coil spring 77 which has one end thereof, as shown at 78, bent at right angles with the main portion 30 of the spring and extending through an aperture in the knurled collar 74. The other end of the spring, as shown at 78', engages a flat finger portion 79 formed on the free end of the arm 76. Formed integrally with the arm 76 and extending 35 upwardly therefrom, is a brake supporting portion 80. On the rear side of the portion 80 is a recess 81 in which is mounted a braking member 82 secured to the brake member 80 by a screw 83. This braking member 82 is preferably made 40 of fibre and is adapted to engage the lower edge of the slide bar 34 as clearly shown in Fig. 13 of the drawings. These brake arms 69 and 76 are pivotally secured to the slide bracket 25' by screws 45 84. Formed integrally with the arm 69 and extending beyond the pivot to the right as viewed in Fig. 2 of the drawings, is an extension 85. Formed integrally with this extension and overhanging the arm 76 is a lug 86 through which extends an adjustable screw 87, the lower end of 50 which engages the upper edge of the arm 76. The adjustable screw 87 is locked in various positions of adjustment by a lock nut 88. Obviously from the above description, it will be readily seen that should the upper surface of the fibre brake 82 become worn, the same may be compensated for by adjusting the stop or screw 87 so as to permit the arm 76 to move upwardly 55 about its pivot with respect to the arms 69 to more effectively brake the slide bar 34. Secured to the slide bracket 25' by means of screws 89 and arranged on the opposite side of the brake member 89 is a bracket or plate 90 which has an inwardly overhanging flange 91 to the under surface of which is secured by means of screws 93, a fibre 60 brake member 92 for engaging the upper side of the slide bar 34.

The slide bar 34 is normally returned to its starting or home position as shown in Fig. 1 against the fibre block or stop 94 secured to the front plate 25 in any well known manner such as a spring 95 which has one end thereof connected to the upper end or arm 96 of a bell-crank 97. The bell-crank 97 is pivotally connected by means of a screw 98 to the front plate 25 as clearly shown in Figs. 1 and 2 of the drawings.

The lower arm of the bell-crank 97 is connected by means of a link 99 to the right hand end of the slide bar 34 as viewed from Figs. 1 and 2. Secured by means of a screw 100 to an upwardly projecting arm 101 formed integrally with the assembler slide bracket 25', is a bell 102. Pivoted on a screw 103 to the assembler slide bracket 25' is a striker arm 104 which is normally actuated in the direction toward the bell by a coiled spring 105. The lower end of the striker arm is provided with a forwardly projecting lug 106 which slides in the path of movement of a downwardly extending projection 107 secured to the rear side of the clamp block 58 by means of a screw 108 as clearly shown in Fig. 20 of the drawings.

The operation of the several features of my invention are as follows:

Let us assume that the operator of the linotype is desirous of setting the clamp 58 on the slide bar 34 for a certain width of a line, the two pawls 20 62 and 63 are depressed and clamp 58 is easily shifted along the slide bar to the approximate position of width of the line, after which the pawls are released, one or the other of pawls, particularly the front ends 64 of one of the pawls 25 will engage one of the notches or recesses 55 in the upper edge of the slide bar in the manner indicated in Figs. 7, 9 and 11 of the drawings. If the operator is desirous of shifting the clamp one way or the other, a distance of six points or the 30 minimum width of the letter "n" matrix, the engaged pawl 62 is depressed and the clamp is shifted in the desired direction and when shifted the proper distance or six points either way, the forward end 64 of the pawl 63 will automatically 35 engage the next adjacent recess 55. This arrangement reduces the time required to set the clamp with respect to the slide bar over the time that is now required for this particular operation. In this connection, it is also pointed out that by 40 reason of the rack teeth on the slide bar being of larger or coarser form, that is the teeth 56 being of "six point" width and the recesses 55 being a "six point" width, the slide bar presents a simpler manufacturing proposition and in combination 45 with this novel, improved clamp, secured the minimum adjustment required for this type of machine with the least possible effort. After the line has been set by the adjustment of the clamp on the slide bar and the matrices discharged into 50 the holding channel in the conventional manner, should additional matrix or matrices be discharged in excess of the line set so as to clog at a point adjacent the star wheel 39 in the manner shown in Fig. 4 of the drawings, the space 55 of the line between the slide finger 34' and the star wheel 39 may be quickly extended without disengaging the clutch 29 to stop the matrix delivery belt 27, by merely depressing the finger trip 44 from the position shown in Fig. 15 to the 60 position shown in Fig. 5 wherein the stop 54 is lowered so as to permit the clamp 58 to move from the position shown in Fig. 15 to the dotted line position shown in Fig. 5, thereby permitting the additional matrices to be added to the line. 65 In this connection, it will also be noted that should the star wheel 39 become worn or a new star wheel replaced for the old one, the stop screw 52 may be adjusted to compensate for any variation necessary to adjust the point at which 70 the clamp and slide bar is stopped.

The operation of another feature which co-operates with the previously described features of my invention has to do with the novel and improved form of braking mechanism for the slide 75

bar which not only permits the adjustment for varying the braking pressure to compensate for wear on the fibre brake, but which also permits a quick release of the brake on the slide bar for taking up any excess of space in the line of matrices after the stop has been released from the clamp to accommodate any excess matrices delivered to the holding channel. This braking mechanism includes an upper fibre brake member 92 secured to the stationary bracket 90 and the spring actuated member 80 which carries the fibre braking member 82 contacting the lower edge of the slide bar 34. It will be noted that when there is an excess space between the slide bar finger 34' and the star wheel 30, this can be immediately taken up by depressing the finger trip 44 against the action of the coil spring 77, releasing the braking tension on the sliding bar so that the returning spring 95 may actuate the slide bar 34 in the direction towards the stop 94. The actuation of the brake member 80 downwardly does not disturb the position of the other brake arm 79. In this connection, it will also be noted that the relative position of the 25 brake arm 76 with respect to the brake arm 69 may be adjusted for taking care of any wear on the fibre brake members. It will also be noted that the spring tension 77 may be adjusted between these two brake arms by merely releasing the screw 54 and turning the thumb sleeve and collar 74 in a counter clockwise direction as viewed from Fig. 6 of the drawings and subsequently tightening the screw 54 when the adjustment has been secured. It will also be observed in this connection, that the manipulation, operation and adjustment of these various features may be accomplished with considerable ease and without interrupting the continuous operation of the machine.

40 From the above description, it will be readily seen that I have provided not only a very simple and efficient means for accomplishing these various operations on the conventional linotype machine, but have also provided a very simple design which expedites the manufacture and reduces the cost as well as increases the efficiency of the whole machine.

While in the above specification I have described one embodiment of my invention, it will 50 of course, be understood that the same is capable of modification and that modification may be made without departing from the spirit and scope of the invention as expressed in the following claims.

55 What I claim is my invention and desire to secure by Letters Patent is:

1. In a typographical machine, the combination of a slide bracket, a slide bar reciprocally mounted on said bracket, a slide clamp mounted on said slide bar, a stop carried by said bracket located in the path of said clamp, and means whereby said stop may be moved out of the path of said clamp for extending the line.
2. In a typographical machine, the combination of a slide bracket, a slide bar reciprocally mounted on said bracket, a slide clamp mounted on said slide bar, a movable stop carried by said bracket and located in the path of said clamp, a spring normally holding said stop in the path of said clamp, and a finger trip whereby said stop may be actuated out of the path of said clamp for extending the line.

3. In a typographical machine, the combination of a slide bracket, a slide bar reciprocally mounted on said bracket, a slide clamp mounted on said slide bar, a guide bracket secured to said first named bracket, a vertically movable member carried by said last named bracket, and a stop member carried by said movable member and located in the path of said clamp for stopping the movement of said slide bar in one direction.

4. In a typographical machine, the combination of a slide bracket, a slide bar reciprocally mounted on said bracket, a slide clamp mounted on said slide bar, a movable stop mounted on said bracket and normally located in the path of said clamp, and means for longitudinally adjusting said stop for varying the length of the line.

5. In a typographical machine, the combination of a slide bracket, a slide bar reciprocally mounted on said bracket, a slide clamp mounted on said slide bar, a vertically movable member mounted on said bracket, a longitudinally adjustable stop carried by said member located in the path of movement of said clamp for varying the length of the line, and a spring normally urging said movable member into the path of said clamp.

6. In a typographical machine, the combination of a slide bracket, a slide bar reciprocally mounted on said bracket, a slide clamp mounted on said slide bar, a guide bracket secured to said first named bracket having a vertical dove-tail slot therein, a vertically movable dove-tail member mounted in said dove-tail slot, a horizontally adjustable stop mounted in said dove-tail member and located in the path of movement of said clamp, and a spring connecting said last named member with said last named dove-tail member for normally maintaining said stop in the path of said clamp.

7. In a typographical machine, the combination of a slide bracket, a slide bar reciprocally mounted on said bracket, a brake for said slide bar including an arm pivoted to said bracket and extending parallel to said slide bar, a second arm pivoted to said bracket and movable in one direction with respect to said first named arm, a braking member carried on the free end of said last named arm, and a spring mounted concentric with respect to the pivots of both of said arms for normally urging one arm in one direction with respect to the other arm.

8. In a typographical machine, the combination of a slide bracket, a slide bar reciprocally mounted on said bracket, a matrix receiving assembler located above one end of said slide bar, a brake mechanism including an arm pivoted to said bracket and extending under said matrix assembler, a second arm pivoted concentric with the first arm, a brake member secured to the free end of said second named arm, a coiled spring mounted concentrically with the pivot of both of said arms and normally urging one of said arms upwardly with respect to the other of said arms, and an adjustable stop carried by said first named arm engageable with said second named arm for varying the brake pressure on said slide bar.
